UNITED STATES PATENT OFFICE.

EMMA MITTELSTAEDT, OF NEW YORK, N. Y.

HAIR-FRONT.

SPECIFICATION forming part of Letters Patent No. 253,412, dated February 7, 1882.

Application filed November 21, 1881. (No model.)

To all whom it may concern:

Be it known that I, EMMA MITTELSTAEDT, of the city, county, and State of New York, have invented certain new and useful Improvements in Hair-Fronts, of which the following is a specification.

This invention relates to an improved construction of hair-fronts for ladies' use, whereby they can be finished in a neater and more durable manner, more easily secured to the hair, and worn with or without parting, as desired.

Heretofore the hair forming a hair-front has been held together by means of a sheet-metal clamp, which was clumsy and did not hold the strands of hair properly. Another mode of attaching the hair in parted fronts was to secure them to a fine piece of gauze, as in the case of wigs, which, however, was expensive, and had the disadvantage that it indicated the artificial nature of the front.

The object of my invention is to form a reliable and permanent connection of the hair constituting the front, either for parted or unparted fronts, and dividing in the latter case the front, so as to show the natural parting of the hair.

In the accompanying drawings, Figures 1 and 2 represent top views of two improved hair-fronts, one being parted, the other unparted; and Figs. 3 and 4 are detail top and bottom views of the connection of the strands of hair with the fastening device.

Similar letters of reference indicate corresponding parts.

Referring to the drawings, A represents my improved hair-front, which may be made either of two parted sections, B, or of one continuous body, as shown respectively in Figs. 1 and 2. The hair is gathered at the middle rear portion of the hair-front into strands *a* of uniform widths, which are secured to a transverse connecting-wire, *b*, and a binding-weft, *d*, or by any other suitable connection by which the hair may be tied together in flat and even manner, the wire being provided with eyes or loops *e* at both ends, for convenient connection to the hair. This binding up of the strands in hair-fronts by a transverse wire and weft forms a durable and permanent connection, as the hair cannot get loose, while it adapts itself evenly to the head, it having throughout a uniform thickness.

Having thus described my invention, I claim as new and desire to secure by Letters Patent—

1. A hair-front composed of waves A, having strands *b* at the rear, connected by a transverse binding-weft, substantially as described. 55

2. A hair-front composed of waves A, having strands *b* at the rear, connected by a transverse binding-weft, provided with eyes and loops at the ends, substantially as described. 60

In testimony that I claim the foregoing as my invention I have signed my name in presence of two subscribing witnesses.

EMMA MITTELSTAEDT.
